AUTOMATIC REGULATION OF THE FORWARD AND BACKWARD MOVEMENT OF THE FABRIC IN LOOMS

Juan Picañol Camps, Sabadell, Spain

Application September 3, 1932, Serial No. 631,628
In Portugal June 18, 1932

2 Claims. (Cl. 139—313)

This invention relates to improvements in take-up movements for weaving looms.

It has been heretofore proposed to impart an intermittent rotary movement to take-up 5 rollers of weaving looms in one direction by means of a pawl and ratchet device or a free wheel device.

If in the course of the operation of the loom it is required for any reason to let back the take-up roller, it is necessary in the known devices to disengage the pawl and ratchet or free wheel mechanism, as normally they would prevent the take-up roller from being turned in the reverse direction. The disengagement of the normal 10 take-up roller drive is a difficult and complicated operation in most constructions, and especially in the case of the more modern free wheel drives, where dismantling of certain parts and subsequent reassembling might become necessary before the normal operation of the loom can be resumed.

In addition, it is desirable that the take-up roller should not be freely rotatable upon the disengagement of the drive but that its let back 25 motion should be positively controlled.

The present invention has for its object to provide an improved take-up movement for weaving looms, wherein the take-up roller can be rotated in a reverse direction in a positively controlled manner at any time without the necessity of interfering with the normal drive, so that the same can remain in engagement as usual while the take-up roller is rotated backwards.

With this object in view and according to the present invention there is provided a take-up movement for weaving looms wherein between the member intermittently driven by a rotating shaft of the loom through a pawl and ratchet or free wheel device and the take-up roller a differential gearing is interposed together with means to rotate said differential gearing bodily in a positively controlled manner in a direction that will produce the required let back movement of the take-up roller.

The invention is illustrated by way of example in the accompanying drawings.

Fig. 1 is a sectional side elevation of the improved take-up movement.

Fig. 2 is a front elevation partly in section, some of the parts being omitted.

Fig. 3 is a front elevation, mainly for illustrating the parts omitted in Fig. 2.

Fig. 4 shows a modification.

Referring to Figs. 1 to 3, the intermittent drive of the take-up roller 15 (Fig. 1) is derived from an axle 23 journaled at 34 in a cylindrical member 35.

The axle 23 is intermittently rotated by an eccentric 32 mounted on a cam shaft 33 (Fig. 3) which is rotated by the driving motor of the loom

in any suitable manner. The eccentric 32 reciprocates a rod 24 the free end of which is secured in a head piece 25 rockably mounted on a pin 36 fixed to a nut 26 (Fig. 1) slidable in the rocker arm 28 and screwed on the threaded spindle 27 which is rotatable in the rocker arm 28 by means of hand wheel 29 but is secured against longitudinal movement therein.

The rocker arm 28 is freely rotatable on the axle 23 and has an annular ledge 37 disposed concentrically thereto. Keyed to the axle 23 at 38 there is a drum 2 whereon the ledge 37 is snugly rotatable, the drum being about twice as wide as the ledge. In the periphery of drum 2 a number of recesses 39 (Fig. 3) are made housing a set of rollers 1, the ledge 37, the drum 2 and the set of rollers 1 constituting a free wheel device which allows rotation of the drum and therewith of the axle 23 keyed thereto in the direction of the arrow in Fig. 3. A second set of 10 rollers 40 is mounted in the recesses 39 at the remaining width of the drum cooperating with an annular ledge 41 of one part 4 of a two part casing 4, 11 housing a differential gearing which 15 transmits the intermittent rotary movement of axle 23 to the take-up roller 15 in a manner hereinafter described. The object of this second set of rollers 40 is to lock the drum 2 against unwanted reverse rotation when the 20 rocker arm 28 is rocked opposite the arrow in 25 Fig. 3. The two sets of rollers are separated by a ring 3 let into a suitable groove in drum 2.

The extent of the movement of rocker arm 28 and therewith that of rotation of the take-up roller 15 is adjusted in a well known manner by 30 turning the hand wheel 29.

The differential gearing through which the intermittent rotation of axle 23 is transmitted to the take-up roller 15 is constructed in the example shown in the following manner:

One part of the axle 23 is formed as a gear 42 (Figs. 1 and 2) meshing with pinions 22 loosely mounted on shafts 21 secured in a gearbox 5 (shaded in criss-cross lines in Fig. 1) rotatably mounted in casing 4, 11. The said pinions 22 are in mesh with pinions 7 mounted on shafts 6, secured in gearbox 5. The said pinions 7 are in mesh with a gear 43 formed at one end of the cylindrical member 35, at the other end of which another gear 18 is formed. The latter is in mesh with a gear 17 rotatably mounted on a shaft 16 fixed to part casing 11. The extended hub of gear 17 carries a pinion 44 in mesh with gear 10 mounted on shaft 8 of the take-up roller 15, the shaft 8 being journaled in part casing 11. A claw clutch 12, 13 actuated by a lever 14 pivoted on the frame 31 of the loom is interposed between the take-up roller 15 and its drive, so that the take-up roller can be completely cut off from its drive if desired.

The differential gearing just described has for its object, as already explained, to enable the take-up roller 15 to be rotated for let-back motion in the reverse direction, without the 5 drive being in any way interfered with.

The mechanism by means of which a let-back motion is obtained in a positively controlled manner is in the example shown constructed as follows:—

10 Rotatably mounted within part casing 11 (Fig. 1) there is a rocker member 19 which at its lower end terminates in a boss in the bore of which is housed a pin 45 in an axially slideable manner. To the lower end of said pin 45 is 15 secured a cross piece 46 which carries a pawl 20 co-operating with ratchet teeth 47 formed on the outer periphery of the gearbox 5. The pawl is normally kept in engagement with the ratchet 47 by springs, not shown. Pivots attached to 20 the upper end of rocker member 19 there is a link 9 to the free end of which is pivotally attached a threaded bolt 48 (Fig. 2) which passes through a hole in the loom frame 31 and has a rimmed nut 30, screwed thereon outside the 25 frame, in such a manner that the nut 30 is applied to a corresponding boss on the frame and when turned causes the rocker member 19 to be rocked.

In the modification shown in Fig. 4 the ratchet 30 teeth 20 on the periphery of gearbox 5 are omitted together with the rocker member 19 and its associated mechanism, and are replaced by a worm shaft 49 and worm 50 mounted in half casing 11 and co-operating with a worm wheel 35 51 secured to gearbox 5 and operated by a hand wheel 52 so that the gearbox 5 together with the pinion mounted therein may be turned in either direction, rotation in one direction effecting the reversal of the take-up roller 15 for let-back motion.

In operation, the free wheel drum 2 is intermittently rotated anticlockwise (Fig. 3) by eccentric 32 connecting rod 24 and rocker arm 28, whereby gear 42 is rotated anticlockwise, pinions 45 22 clockwise, pinions 7 anticlockwise, member 35 clockwise, gear 17 and pinion 44 anticlockwise, gear 10 and therewith take-up roller 15 clockwise.

If now it is desired to reverse the direction of 50 rotation of the take-up roller 15 for let-back motion, the normal drive is stopped and gearbox 5 is turned by means of the nut 30 or hand wheel 51 clockwise whereby pinions 7 in being taken round therewith are rotated clockwise, member 55 35—the pinion 43 of which is in mesh therewith—is rotated anticlockwise, gear 17 and pinion 44 clockwise, gear 10 and therewith the take-up roller 15 anticlockwise, i. e. in a direction reversed to the usual drive.

60 It is understood that the construction described and illustrated by way of example is capable of various modifications in construction and arrangement without departing from the spirit of the invention, thus for example any 65 other suitable type of differential gearing may be used and the free wheel drive may be replaced by a pawl and ratchet drive.

I claim:

70 1. A device for regulating the forward and backward movement of fabric on looms, comprising in combination with the loom frame a driving shaft journalled in said frame, a cam on said shaft, a connecting rod adapted to be recip-

rocated by said cam, an oscillatable lever connected at one end to said connecting rod and having a recess at its other end, a ring having wedge shaped recesses distributed around its circumference and projecting partly with one half into the recess in said lever, a casing surrounding the other half of said ring, two sets of rollers in said wedge shaped recesses in said ring one set within the recess of said lever and adapted to jam between said ring and said lever to cause said ring to rotate with said lever when same swings in one direction and to slide back into said wedge shaped recesses to allow said lever to move independently of said disc in the other direction, the other set of rollers within said casing adapted to allow said ring to rotate with said lever in one direction and to jam between said ring and said casing to lock said ring against rotation when said lever swings in the other direction, a pinion rigidly connected to 10 and adapted to be rotated in one direction by said ring, a differential gearing cooperating with said pinion to transmit the movement of said ring, a fabric winding drum connected to said differential gearing adapted to be driven in one direction by said gearing, a disc carrying said 15 gearing, a ratchet wheel on the periphery of said disc, a pawl engaging said ratchet wheel, and means for shifting said pawl to rotate said ratchet wheel to turn said roller in the opposite 20 direction to that imparted by said ring through the intermediary of said gearing.

2. A device for regulating the forward and backward movement of fabric on looms, comprising in combination with the loom frame, a 35 driving shaft journalled in said frame, a cam on said shaft, a connecting rod adapted to be reciprocated by said cam, an oscillatable lever connected at one end to said connecting rod and having a recess at its other end, a ring having wedge shaped recesses distributed around its circumference and projecting partly with one half into the recess in said lever, a casing surrounding the other half of said ring, two sets of rollers in said wedge shaped recesses in said ring one set within the recess of said lever and adapted to jam between said ring and said lever to cause said ring to rotate with said lever when same swings in one direction and to slide back into said wedge shaped recesses to allow said 40 lever to move independently of said disc in the other direction, the other set of rollers within said casing adapted to allow said ring to rotate with said lever in one direction and to jam between said ring and said casing to lock said ring against rotation when said lever swings in the other direction, a pinion rigidly connected to 45 and adapted to be rotated in one direction by said ring, a differential gearing cooperating with said pinion to transmit the movement of said ring, a fabric winding drum connected to said differential gearing adapted to be driven in one direction by said gearing, a disc carrying said 50 gearing, a ratchet wheel on the periphery of said disc, a pawl engaging said ratchet wheel, a worm screw thread on the periphery of said disc, a worm engaging said worm screw thread, and means for rotating said worm to cause said disc 55 to rotate in the opposite direction to that imparted by said ring through the intermediary of said gearing.

JUAN PICAÑOL CAMPS.
